CLAIM

The ornamental design for a cassette for a sewerless toilet, substantially as shown and described.

DESCRIPTION

FIG. 1 is a left side elevational view of a cassette for a sewerless toilet embodying our new design, the right side being a mirror image of the left side shown;

FIG. 2 is a top plan view thereof;

FIG. 3 is a front elevational view thereof;

FIG. 4 is a rear elevational view thereof; and

FIG. 5 is a bottom plan view thereof.

FIG. 1

F I G. 2
